(57) **CLAIM**

The ornamental design for a tape printing machine, as shown and described.

DESCRIPTION

FIG. 1 is a perspective view of a tape printing machine,
FIG. 2 is a front view thereof;
FIG. 3 is a top view thereof;
FIG. 4 is a right-side view thereof, the left-side view being a
mirror image of the right-side view;
FIG. 5 is a rear view thereof; and,
FIG. 6 is a bottom view thereof.

The broken lines depict unclaimed portions only and form no
part of the claimed design.
